UNITED STATES PATENT OFFICE

2,438,602

DISPENSER

Frederick De Cesaris, Johnston, R. I., assignor to
James Manufacturing Company, Inc., Providence, R. I., a corporation of Rhode Island

Application September 12, 1947, Serial No. 773,629

6 Claims. (Cl. 312—73)

1

This invention relates to a dispenser for slender articles.

More particularly, the invention relates to a dispenser having a normally sealed article magazine which may be reciprocated along a supporting standard to give access to any one of a plurality of slender articles in the receiving magazine. More specifically the dispenser is intended to facilitate substantially hermetic storage and orderly dispensing of such articles as cigarettes, matches, toothpicks, and the like.

It has been known heretofore to provide dispensing devices for articles of the nature for which this dispenser is adapted but such prior dispensers have been subject to the disadvantage that a single article is presented through an opening in the top of the article holding magazine when the dispenser is operated. Such prior devices made no provision for access to all of a plurality of articles within the dispensing magazine and yet provide a structure wherein the magazine is substantially hermetically sealed against external atmosphere that would deteriorate or contaminate the contents of the magazine.

In its most specific sense the dispenser comprises a base and a guide rod extending upwardly from the base along which the article holding magazine is reciprocated while the articles to be dispensed rest upon a stationary platform fixed to the standard so that the upper ends of the articles are presented through the upper open end of the article magazine.

The invention will be more readily understood by reference to the drawing forming a part of this application and in which drawing:

Figure 1 is a perspective view of the dispenser.

Figure 2 is a longitudinal sectional view, and;

Figure 3 is a transverse view partly in section and partly in full lines taken along the line 3—3 of Figure 2.

With specific reference to the elements illustrated in the drawing, the dispenser includes a base 10, and a guide rod 12, affixed to the base 10 and extending upwardly therefrom. An article receiving magazine 14 which has an open upper end 16 is mounted for reciprocating movement along the upstanding guide rod 12. A cover member 18 which is of the same shape and somewhat larger than the open end 16 of the article receiving magazine is fixed to the upper end of the standard 12 in any suitable fashion, for example a nut 20 threaded to the upper threaded end 22 of the standard 12, as shown herein.

A spring 24 is interposed between the base 10

5 and the lower end of the article magazine 14 and this spring is under sufficient tension to maintain the magazine 14 in its elevated position wherein the upper open end thereof lies in contact with the lower face of the cover member 18. In its specific embodiment the spring herein is a coil spring positioned about the upstanding guide rod 12. Both the guide rod 12 and its surrounding spring 24 are enclosed by means of telescopic tubular members. Thus, a tubular member 26 extends upwardly from the base 10 and encloses the lower end of the rod 12 as well as the lower end of the spring 24. A second tubular member 28 is fixed to the lower end of the article magazine 14 and depends therefrom into telescopic relation with respect to the lower tubular member 26. It will be noted that the respective lengths of the tubular members 26 and 28 are such that the magazine 14 may be reciprocated downwardly along the guide rod 12 into the dot and dash line position in Fig. 2.

In order to render the dispensing magazine substantially air tight there is provided herein a deformable annular sealing gasket which lies between the peripheral lip of the open upper end of the magazine 14 and the lower face of the closure member 18. In the specific embodiment the deformable sealing member is shown as the sealing gasket 30 which embraces the peripheral lip 32 of the dispensing magazine 14. The pressure of the spring 24 is sufficient to deform the sealing gasket 30 to an extent that is sufficient to effect a substantially air tight contact between the upper face of the gasket 30 and the bottom face of the closure member 18.

Within the article magazine 14 is a stationary platform 32 for supporting the articles within the magazine. It will be observed, therefore, that as the magazine 14 is moved downwardly against the tension of the spring 24 any articles supported by the fixed platform 32 will be accessible above the lip of the open end of the dispensing magazine. In other words, the magazine 14 is moved away from the articles on the fixed supporting platform 32 so that free access is given to any one of a plurality of articles within the magazine.

It follows, therefore, that the foregoing structure achieves the objects of the invention by providing a dispensing magazine wherein all of a plurality of articles within the magazine are accessible on each operation of the dispenser while at the same time the articles are protected within the magazine in an atmosphere that is sealed

against deteriorating or contaminating external atmosphere.

While having described the invention in its presently preferred form, the practice thereof shall be limited only by the scope of the following claims.

I claim:

1. A dispenser for slender articles comprising, a base, a guide rod extending upwardly from said base, an article magazine open at its upper end mounted on said guide rod for reciprocating movement therealong, a fixed article supporting platform within said magazine, a cover member fixed to the upper end of said guide rod, and a spring tensioned to normally maintain the open upper end of said magazine in contact with said cover member.

2. A dispenser for slender articles comprising, a base, a guide rod extending upwardly from said base, an article magazine open at its upper end mounted on said guide rod for reciprocating movement therealong, a fixed article supporting platform within said magazine, a cover member fixed to the upper end of said guide rod, a resilient sealing member carried by one of said last two mentioned members, and a spring tensioned to normally maintain the open upper end of said magazine in contact with said cover member.

3. A dispenser for slender articles comprising, a base, a guide rod extending upwardly from said base, an article magazine open at its upper end mounted on said guide rods for reciprocating movement therealong, a fixed article supporting platform within said magazine, a cover member fixed to the upper end of said guide rod, a coil spring positioned about said guide rod and extending between said base and the lower end of said magazine under tension to normally maintain the open upper end of said magazine in contact with said cover member.

4. A dispenser for slender articles comprising, a base, a guide rod extending upwardly from said base, an article magazine open at its upper end mounted on said guide rod for reciprocating movement therealong, a fixed article supporting platform within said magazine, a cover member fixed to the upper end of said guide rod, a tubular

member extending upwardly from said base and enclosing the lower end of said guide rod, a second tubular member depending from the bottom of said magazine disposed in telescopic relation with respect to said first tubular member, and a spring tensioned to normally maintain the open upper end of said magazine in contact with said cover member.

5. A dispenser for slender articles comprising, a base, a guide rod extending upwardly from said base, an article magazine open at its upper end mounted on said guide rod for reciprocating movement therealong, a fixed article supporting platform within said magazine, a cover member fixed to the upper end of said guide rod, a coil spring positioned about said guide rod and extending from said base to the lower end of said magazine for normally maintaining the open upper end of said magazine in contact with said cover member, a tubular member extending upwardly from said base and enclosing the lower end of said rod and spring, and a second tubular member depending from the bottom of said magazine disposed in telescopic relation with respect to said first mentioned tubular member.

10 6. A dispenser for slender articles comprising, a base, a guide rod extending upwardly from said base, an article magazine open at its upper end mounted on said guide rod for reciprocating movement therealong, a fixed article supporting platform within said magazine, a cover member fixed to the upper end of said guide rod, a coil spring positioned about said guide rod and extending from said base to the lower end of said magazine for normally maintaining the open upper end of said magazine in contact with said cover member, a tubular member extending upwardly from said base and enclosing the lower end of said rod and said spring, a second tubular member depending from the bottom of said magazine disposed in telescopic relation with respect to said first mentioned tubular member, and a deformable annular sealing gasket lying between the peripheral lip of said magazine and in contact with the lower face of said cover member.

FREDERICK DE CESARIS.
